UNITED STATES PATENT OFFICE.

LAFAYETTE T. BOW, OF BURKSVILLE, KENTUCKY.

ENTRANCE-TUBE FOR GRAIN-VENTILATORS.

SPECIFICATION forming part of Letters Patent No. 266,083, dated October 17, 1882.

Application filed August 18, 1882. (No model.)

To all whom it may concern:

Be it known that I, L. T. Bow, of Burks-ville, in the county of Cumberland and State of Kentucky, have invented certain new and use-
5 ful Improvements in Entrance-Tubes for Grain-
Ventilators; and I do hereby declare that the
following is a full, clear, and exact description
thereof, reference being had to the accompan-
ying drawing, and to the letters of reference
10 marked thereon, which forms part of this speci-
fication, in which the figure is a diametrical
section through my improved grain-ventilator.

This invention relates to grain and hay ven-
tilators, the object of which is to allow a free
15 circulation of air in a body of grain or hay for
the purpose of preventing heating, souring, or
general deterioration of the product; and the
nature of my invention consists in a tapered
and perforated tube wound in a spiral form,
20 and connected removably to a straight perfor-
ated tube having a T-wrench secured to it, as
will be hereinafter fully explained.

The letter A designates a straight tube, which
may be of any desired length, and which is
25 thickly perforated, as shown. This tube has
inserted into one end a plug, E, which is rig-
idly secured to a T-shaped head, D, forming
two hand levers or wrenches, by which the ven-
tilator can be forcibly introduced into a hay-
30 mow or into a body of grain. The plug E is
connected to the perforated tube A by means
of a pin, F, which is preferably attached by a
cord or chain, a, to one of the arms of the head
D. By removing the pin F the head and its
35 plug can be detached from the tube A, thus
leaving the end thereof open for free ventila-
tion.

B designates a spiral penetrating-point,
which is a tube thickly perforated and tapered,
so that it terminates in a point, C. This spiral 40
or screw-shaped penetrating-point B is attached
to the straight tube A by means of a pin, F',
so that when desired the said point can be de-
tached from the tube A. I prefer to use coni-
cal wood points C, although these points may 45
be made of metal, and they may be removably
attached to the perforated tube A by means of
a pin or by means of a screw.

It will be seen from the above description
that I have a ventilator which is composed of 50
a straight tube terminated by a spiral pene-
trating-point, both the point and tube being
perforated for the purpose of affording free
ventilation and circulation of air. It will also
be seen that I provide my ventilator with a re- 55
movable handle or wrench, which is used for
inserting the instrument into a body of grain
or hay by a screwing action.

Having described my invention, I claim—

A grain or hay ventilator consisting of a 60
straight perforated tube, A, a wrench, D, a
plug, E, a pin, F, a tapered spiral penetrat-
ing-tube, B, detachable from the tube A and thickly
perforated, and the solid removable penetrat-
ing point C, all constructed and adapted to op- 65
erate substantially as described.

In testimony that I claim the foregoing as
my own I affix my signature in presence of two
witnesses.

LAFAYETTE TAYLOR BOW.
